<img alt="Technical drawing of a cross-section of a device assembly. The drawing shows a top cover 5 with a central slot 11. Below the cover is a base 7 containing two vertical components 12. Each component 12 has a horizontal slot 13 at the bottom and a vertical slot 14 in the middle. A central horizontal slot 15 is located in the base 7 between the two components 12. Numbered callouts point to various parts: 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, UNITED STATES PATENT OFFICE.

WALTER C. LOK AND KARL H. LOK, OF TOLEDO, OHIO.

MAIL-BAG CATCHER.

1,158,697.

Specification of Letters Patent.

Patented Nov. 2, 1915.

Application filed December 12, 1914. Serial No. 876,944.

To all whom it may concern:

Be it known that we, WALTER C. LOK and KARL H. LOK, citizens of the United States, residing at Toledo, in the county of Lucas and State of Ohio, have invented new and useful Improvements in Mail-Bag Catchers, of which the following is a specification.

The present invention relates to improvements in means for delivering an article to a moving body.

The invention is primarily directed to means arranged upon a railway car and is adapted to receive and convey a mail bag from a station to the said car.

15 The primary object of the invention is to construct a device of this character wherein the jar incidental to the engagement of the conveying apparatus with the bag will be so decreased that all probability of damage to 20 the bag or to any of the elements comprising the device will be decreased to a minimum.

With the above and other objects in view, the improvement resides in the construction, combination and arrangement of parts set 25 forth in the following specification and falling within the scope of the appended claim.

In the drawings: Figure 1 is a side elevation of a mail car and a station post, provided with our improvement, and illustrating 30 the delivery apparatus about to grasp a mail bag to deposit the same within the car, Fig. 2 is a horizontal sectional view approximately on the line 3—3 of Fig. 1, Fig. 3 is a view looking toward the end of the 35 car and the station post, the car being partly broken away, Fig. 4 is an enlarged transverse section through the track of our improvement showing the conveyer in position thereon, and Fig. 5 is a perspective 40 view of the station post.

Referring now to the drawings in detail, the numeral 1 designates an ordinary mail car and 2 a station post which is arranged to one side of the tracks upon which the 45 car travels. The post, in the present instance, is provided with a metallic head 3 having formed thereon, at its upper portion, a pair of spaced curved arms 4—4.

Secured to suitable arms 5 which are pivotally connected with the brackets 6 that are secured at spaced intervals upon the side of the car 1 is an inclined track 7. The ends of this track may be and preferably are straight, the outer straight end being 50 indicated by the numeral 8 and the inner straight end, indicated by the numeral 9

has its extremities curved inwardly through the doorway of the car, as indicated by the numeral 10. The track comprises a top member 11 having angular depending spaced sides 12—12, and the said sides are provided with inturned flanges 13—13, the said flanges being spaced a suitable distance apart to form the tracks proper or the bearing surface for roller members 14—14, preferably four in number, two being arranged upon each of the flanges 13.

The numeral 15 designates a suitable frame or truck provided with axles 16 which are received within the bore or bores 70 of the rollers 14, and the truck 15 is provided with a depending member 17 having an outer hook shaped end. The end 8 of the track is closed, as indicated by the numeral 18 so as to prevent the outward movement of the truck or carriage 15 when the same is permitted to gravitate down the inclined track 7 to bring its hook into bag-engaging position, as illustrated in Fig. 1 of the drawings. Likewise the inclined 80 curved end 10 may be closed if desired, as the bag may be delivered from the hook, after the truck or carriage 15 is caused to travel within the car, as will readily be understood.

The mail sack is indicated by the numeral 19, the same being provided with the usual handle 26 which is received on the hook 17. When the hook passes through the handle the momentum of the car will cause the carriage 15 to travel up the inclined track 7 and the rounded end 10 thereof to within 85 the car, the mail bag offering a resistance to the wind and thus insuring its upward travel and delivery. When the device is 90 not in use the track is swung upon its pivotal connection with the brackets 6 and locked against the side of the car through the medium of suitable locking means 27 so that the same will not meet with obstructions during the travel of the car. When 95 the device is to be again positioned to receive another sack of mail, the track 7 is swung to its horizontal position and the carriage 15 is permitted to gravitate down 100 the track until the same is in engaging position, the carriage being of sufficient weight to permit of such gravitation and being so shaped as to offer a small resistance to the wind.

From the above description, taken in connection with the accompanying drawings,

the simplicity of the device as well as the advantages thereof will, it is thought, be perfectly apparent to those skilled in the art to which such invention appertains 5 without further detailed description.

Having thus described the invention, what we claim is:

10 A railway car having spaced angularly arranged brackets, a track, arms upon the track pivotally secured to the brackets, a

carriage movable upon the track, means for locking the track to the car when the same is swung upon the brackets.

In testimony whereof we affix our signatures in presence of two witnesses.
